TRASH RECEPTACLE

Eleanor V. Kingsley, P.O. Box 104, Pomona, Calif.

Filed Aug. 3, 1964, Ser. No. 51,122

Term of patent 14 years

(Cl. D58—17)

FIG. 2.

FIG. 3.

FIG. 1 is a perspective view of a trash receptacle, showing my new design.

FIG. 2 is a front elevational view thereof.

FIG. 3 is a side view.

The side of the receptacle not shown is the same as the one shown, the hinge element appearing at the right instead of at the left, as in FIG. 3. Except that the hinge element is omitted, the rear of the receptacle is the same as the front.

I claim:

The ornamental design for a trash receptacle, substantially as shown and described.
